UNITED STATES PATENT OFFICE.

WILLIAM M. SHERMAN, OF OMAHA, NEBRASKA.

STEPLADDER.

Application filed August 2, 1923. Serial No. 655,190.

To all whom it may concern:

Be it known that I, WILLIAM M. SHERMAN, a citizen of the United States, residing at Omaha, in the county of Douglas and 5 State of Nebraska, have invented certain new and useful Improvements in Stepladders, of which the following is a specification.

The present invention relates to step ladders and particularly to those of the adjustable type.

An object of the present invention is to provide a ladder of this type which may be used as an ordinary step ladder, as an extension ladder, an ordinary leaning ladder, or a ladder which may be adjusted to various irregular conditions met with in the floors, stairs or other supports.

Another object of the invention is to provide a ladder which comprises a pair of medium sized sections so constructed and provided with devices that permit of the adjustment of these sections to adapt the ladder for general household use by mechanics such 25 as paper hangers, painters and the like.

A further object of the invention is to provide a ladder of this character which may be used upon stair-ways and in halls for supporting planks or the like for use 30 by mechanics and which need not come in contact with the walls, and which will not mar or destroy any of the flooring, stairs or coverings therefor.

A still further object of the invention is 35 to provide an improved construction of ladder which embodies a novel interlocking means for securing the sections one upon the other in interbracing position and with the supporting section of the ladder at various heights, and which also provides a novel connection between the ladder sections 40 which permit the sliding of one upon the other and the securing of one section in an extended position from the other.

With the foregoing and other objects in 45 view, the invention will be more fully described hereinafter, and will be more particularly pointed out in the claim appended hereto.

50 In the drawings, wherein like symbols re-

fer to like or corresponding parts throughout the several views,

Figure 1 is a side elevation of a ladder constructed according to the present invention and set up on a stair-way and in the 55 hall leading thereto, the ladder supporting a plank or scaffold section.

Figure 2 is a top plan view of the ladder.

Figure 3 is a longitudinal section taken through the ladder extended and leaning 60 against a wall.

Figure 4 is a front elevation of the same.

Figure 5 is a side elevation of the ladder adjusted for use as a common step ladder.

Figure 6 is a fragmentary side elevation 65 of the upper end of the supporting and extension section of the ladder, and

Figure 7 is a fragmentary enlarged longitudinal section through the upper end of the step portion of the ladder, showing the 70 supporting and extension section in dotted lines and in position to support the ladder as shown in Figure 5.

Referring to the drawings the ladder comprises two sections, a step or main section and a supporting or extension section.

The main or step section of the ladder comprises a pair of side rails 10 of suitable length which support therebetween a plurality of steps 11 which are preferably 80 morticed in the inner sides of the rails 10. These steps 11 are provided near their inner edges and in spaced relation to the side rails 10 with pairs of openings 12 for a purpose which will hereinafter appear. As 85 shown to advantage in Figure 7, the side rails 10 are provided at their upper ends with coupling plates 13 which may be edge-wise extensions of the side rails 10 or which may be otherwise suitably formed upon the 90 upper ends of the side rails to project beyond the inner edges of the side rails. These coupling plates 13 have in their inner opposite faces longitudinal slots 14 extending substantially parallel with the edges of the 95 side rails 10 and which open through the upper and lower edges of the coupling plates 13.

The coupling plates 13 are further provided with slots or recesses 15 formed in the 100

inner opposite faces of the plates 13 and which intersect the intermediate portions of the slots 14 at an angle of substantially 45 degrees thereto. The slots 15 provide at 5 opposite sides of the slots 14 oppositely facing seats or shoulders 16 for a purpose which will hereinafter appear. The coupling plates 13 are connected together at their rear edge portions by a cross rod 17 which 10 is spaced inwardly from the plane of the inner edges of the side rails 10 and which is also located beyond the slots 14 and 15.

The other section of the ladder which 15 comprises the supporting or extension section is provided with side rails 18 connected together by a plurality of rungs 19 and being of a width adapted to fit between the coupling plates 13 of the main ladder section. The upper ends of the side rails 20 18 are provided with laterally projecting stops 20 arranged to overhang the coupling plates 13 and engage the upper edges of the ladder for holding the supporting sections from sliding downwardly from between the 25 coupling plates. The lower end of the supporting and extension section of the ladder is provided with a pair of curved hooks 21 which are pivoted upon bolts 22 or the like carried in the lower ends of the rails 18 of the extension section and which are arranged to swing outwardly and into the openings 12 of an adjacent step of the main ladder section so as to interlock the two sections in extended position and at the desired length. The hooks 21 combined with the cross rod 17 of the main section hold the two sections firmly in extended position as shown in Figures 3 and 4.

The secondary section of the ladder, which 40 is the supporting and extension section, is provided at opposite sides and at suitably spaced apart points in the length of the section, with pairs of interlocking ears 23 which are of a width adapted to slide longitudinally through the slots 14 of the coupling plates and which are of a length adapted to snugly fit the cross slots 15 when the secondary ladder section is swung into the position at substantially 45 degrees to the main section, as shown in dotted lines in Figure 7.

In this instance the ears have opposite ends engaging the shoulders or seats 16 of the slots 15 and hold the secondary section from not only sliding through the plates 13 but also from swinging between the plates. These ears 23 are brought into line with the cross slots 15 by sliding the secondary ladder section through the plates 60 so that the upper pairs of ears 23 may be interlocked with the coupling plates 13 as shown in Figures 5 and 7, or the intermediate pair of ears 23 may be interlocked with the coupling plates 13 as shown in Figure 1 and under such conditions where the

supporting surface of the secondary section is higher than the supporting surface of the main section.

Of course the ears 23 may be provided in any suitable positions upon the secondary 70 ladder section and may be spaced apart as desired to meet the conditions of use. It will also be noted from Figures 6 and 7, particularly, that the upper pair of ears 23 when moved downwardly in the slots 14 of 75 the coupling plates are permitted to pass below the cross slots 15 before the stops 20 engage the coupling plates for suspending the secondary ladder section from the coupling plates. In this position the upper ears hold 80 the secondary section from swinging inwardly away from the step or main portion of the ladder and serve in conjunction with the cross rod 17 as a means for suitably bracing and holding the two sections of the ladder firmly together.

From the above it is thought that the adjustments of the device for various uses will be understood and it may be pointed out that the secondary section can be elevated 90 between the coupling plates 13 until the desired pair of ears 23 registers with the cross slots 15. The secondary section is now swung inwardly at its lower end away from the main section and such operation swings 95 the selected pairs of ears 23 into the cross slots 15 and against the seats or shoulders 16. The lower end of the secondary section is now rested upon the floor or support and the sections of the ladder are held 100 interlocked at the desired angle. This adjustment is shown in Figure 1 for the lower pair of ears and in Figure 5 for the upper pair of ears.

When to be used as an extension ladder 105 the secondary section is merely slid upwardly through the coupling plates 13 until the desired height is reached when the hooks 21 are swung outwardly and through the openings 12 of the adjacent step 11.

I do not wish to be restricted to the size, form, and proportions of the various parts, and obviously changes could be made in the construction herein described without departing from the spirit of the invention, it 115 being only necessary that such changes fall within the scope of the appended claim.

What is claimed is:—

A step ladder comprising a main section and an extension section, a pair of plates projecting rearwardly from the upper end of the main section and having registering slots in their inner opposite faces extending substantially in parallel relation with the main section, said plates having shouldered recesses in their inner opposite faces intersecting the slots and extending at an angle thereto, and lateral projections arranged in pairs at opposite sides of said extension section and adapted to freely slide through 125

said slots of the plates when the extension section is swung into parallel relation with the main section for adjusting the extension section along the main section, said lateral projections of the extension section being adapted to enter said recesses and bear against the shoulders thereof when the extension section is swung into an angle with

respect to the main section for locking the two sections against relative movement. 10

In testimony whereof I have affixed my signature in presence of two witnesses.

WILLIAM M. SHERMAN.
